[57] CLAIM

The ornamental design for a staple remover, as shown and described.

DESCRIPTION

FIG. 1 is a perspective view of a staple remover showing my new design;

FIG. 2 is a perspective view thereof of the top member shown separately for clarity of illustration;

FIG. 3 is a perspective view thereof of the bottom member shown separately for clarity of illustration;

FIG. 4 is a right side elevational view thereof in a closed position;
The undisclosed left side elevational view is a mirror image of the right; and

FIG. 5 is a front elevational view thereof in a closed position.
